Primary Examiner — Marie D. Fast Horse(74) *Attorney, Agent, or Firm* — The Jansson Firm; Pehr B. Jansson(57) **CLAIM**

The ornamental design for a capture device, as shown and described.

DESCRIPTION

FIG. 1 is a perspective view of a capture device, showing our new design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The broken lines in the drawings depict portions of the capture device that form no part of the claim. Any surface shading illustrated in the drawings is provided merely to highlight contour of design and is not intended to be illustrative of texture or gloss.
